UNITED STATES PATENT OFFICE

GRACE J. LYONS, OF BRONX, NEW YORK, ASSIGNOR, BY MESNE ASSIGNMENTS, TO ELASTO RIBBON CO., INC., OF NEW YORK, N. Y., A CORPORATION OF NEW YORK

GARMENT SUPPORTER

Application filed December 4, 1931. Serial No. 578,911.

This invention relates to improvements in apparel, and more particularly it pertains to a novel construction and form of garment supporter.

5 It is a well recognized fact that shoulder straps as commonly employed are a source of great annoyance to the wearer, since under certain conditions, they will invariably ride over the shoulders and have continuously to 10 be replaced by the wearer.

It is one of the objects of the present invention to improve the construction of garment supporters generally and particularly those of the shoulder strap type.

15 A feature of the invention resides in the combination in a novel manner of an elastic member and an inelastic member to provide a novel garment supporting strap.

A further feature of the invention resides 20 in a novel arrangement and resultant novel method of operation of elastic elements in combination with an inelastic element in devices of the aforementioned character.

A still further feature of the invention resides 25 in a novel garment supporter which may be worn without even the slightest discomfort, and yet which will retain its proper position upon the body of the wearer under all conditions of use.

30 With the above and other objects in view, reference will be had to the accompanying drawing wherein is illustrated one embodiment of the invention, and wherein;

Figure 1 is a view in elevation illustrating 35 the invention as applied to the shoulder straps of a ladies' under garment;

Figure 2 is a fragmentary plan view of a portion of a shoulder strap constructed in accordance with the present invention, the 40 strap being relieved of all tension,

Figure 3 is a similar view showing the strap placed under tension and extended to the fullest extent,

Figure 4 is a detail longitudinal sectional 45 view taken on the line 4-4 of Figure 2,

Figure 5 is a longitudinal sectional view taken on the line 5-5 of Figure 3, and

Figure 6 is a transverse sectional view taken on the line 6-6 of Figure 2.

50 A garment supporter constructed in ac-

cordance with the present invention consists of a main body portion of inelastic material and one or more elastic elements such as 11 associated therewith.

The inelastic body portion 10 may be constructed in any desired manner, but I prefer to weave the same in the form of a tape or ribbon like member which may be formed in the desired length for use, but which is preferably formed in long lengths from which the 60 desired length for use may be severed.

The elastic elements 11 of which there are four shown in the present embodiment of the invention, extend longitudinally of the inelastic body portion. These elastic elements 65 are preferably formed from single strands of rubber of a high degree of elasticity and in their manner of use in the present invention would not of themselves support a garment in position on the wearer.

By reference to the drawing it will be noted that although the elastic elements are shorter than the inelastic body portion, they do extend throughout the entire length thereof. This arrangement of elastic and inelastic 75 members causes the inelastic member to gather as illustrated in the drawing at 12 when the elastic members are not under tension, but leaves these elastic elements free to stretch when the inelastic member is stretched 80 lengthwise even to its fullest extent as shown in Figure 3.

While in my many experiments I have found that the elastic elements may be combined with the inelastic body portion in various ways, I prefer to embody them during the weaving operation which forms the inelastic body portion, and in so doing, I prefer to maintain the elastic elements under tension during the weaving operation. By 90 this method, as soon as the tension of the elastic elements is released, the article takes the form illustrated in Figures 2, 4 and 6, and presents a neat and attractive appearance.

In the present illustration, I have shown 95 the invention embodied in the shoulder straps of a ladies undergarment, and I will now describe its manner of use and the manner in which it functions when used in this connection.

When used as shoulder straps, the tape or ribbon like member is cut to such a length that it will be the correct length for use when stretched to its fullest extent as illustrated in Figure 3. This length is then secured at its ends to the garment in any desired manner. When the garment is not in use, the main body portion 10 will of course be gathered as at 12 under the influence of the elastic elements 11. When, however, the garment is placed in position upon the body of the wearer, the shoulder straps immediately stretch to their fullest extent as illustrated at the left hand side of Figure 1. This is true since as before stated, the elastic elements will never be of such strength, nor will they be used in such numbers, as to in themselves be sufficient to support any garment with which they are used.

At the left hand side of Figure 1, the shoulder strap is illustrated in its normal position, and it will be noted that it presents a neat and smooth appearance, and is to all purposes the same in appearance as the ordinary tape or ribbon so generally employed for this purpose.

At the right hand side of Figure 1, I have illustrated the manner in which the shoulder strap functions under conditions of wear. It will be noted that the left shoulder of the figure illustrated in Figure 1, has drooped. This drooping of the shoulder would, in ordinary shoulder straps, produce sufficient slack to cause the shoulder strap to ride off the shoulder and down along the arm from whence it would have to be replaced by the wearer.

In a shoulder strap constructed in accordance with the present invention, however, any slack occurring in the shoulder strap as a result of any movement of the body is immediately taken up by the elastic elements as indicated by the gathered portion 12 at the right hand side of Figure 1, and the shoulder strap is maintained in position as shown. Immediately the body of the wearer resumes its normal position, the elastic elements are placed under tension and the inelastic body portion again assumes a smooth and neat appearance as illustrated at the left side of Figure 1.

I am aware that elastic webbing has been combined with inelastic material in garment supporters, and even in garment supporters of the shoulder strap type, but in all such cases with which I am familiar, the elastic material is employed to provide the necessary stretch or give to permit of free movement of the body of the wearer. Furthermore, elastic webbing as ordinarily constructed could not be employed in the manner herein described for the reason that it would under tension, cut into the shoulders of the wearer, and would also result in disarrangement of the garment since elastic webbing when

stretched would have sufficient strength in itself to pull the garment out of proper wearing position.

While I have herein illustrated my invention as embodied in the shoulder straps of a ladies undergarment, it will be obvious that it is also applicable to other embodiments, and I therefore do not wish to be limited to this use solely, nor do I wish to be limited to any particular number of elastic elements since they may be employed in any number so long as they are insufficient in themselves to support the garment in connection with which they are used.

While I have herein illustrated the elastic element as extending along the side edges of the inelastic body portion, this particular arrangement of parts is not essential to the invention, since the elastic elements may be combined with the inelastic body portion in any desired manner.

Having thus described the invention, what is claimed as new, and what it is desired to secure by Letters-Patent of the United States, is;

1. A supporter for attachment to a garment, said supporter comprising an elongated inelastic element, a take-up means comprising one or more elastic elements combined with said inelastic element, the elasticity of the take-up means being sufficient to take up slack in the inelastic member, but insufficient alone to support the garment to which it is attached.

2. A supporter for attachment to a garment, said supporter comprising an elongated inelastic woven fabric element, a take-up means comprising one or more parallel strands of rubber combined with said inelastic element and extending longitudinally thereof throughout its length, the elasticity of the take-up means being sufficient to take up slack in the inelastic member, but insufficient alone to support the garment to which it is attached.

3. In combination with a garment, resilient means therefor, said supporting means comprising an elongated inelastic element, a take-up means comprising one or more elastic elements combined with said inelastic element, the elasticity of the take-up means being insufficient alone to support the garment to which the supporter is attached and so constructed and arranged that when the garment is in position upon the wearer, the take-up means will be stretched to substantially its elastic limit.

Signed at New York city in the county of New York and State of New York this second day of November A. D. 1931.

GRACE J. LYONS.

CERTIFICATE OF CORRECTION.

Patent No. 1,887,939.

November 15, 1932.

GRACE J. LYONS.

It is hereby certified that error appears in the printed specification of the above numbered patent requiring correction as follows: Page 2, line 112, claim 3, before "means" first occurrence insert the word "supporting"; and that the said Letters Patent should be read with this correction therein that the same may conform to the record of the case in the Patent Office.

Signed and sealed this 17th day of January, A. D. 1933.
